CONVERSION OF CARBONACEOUS MATERIALS

Earl W. Ribblett, Tenafly, N. J., assignor to Hydro-carbon Research, Inc., New York, N. Y., a corporation of New Jersey

Application August 9, 1947, Serial No. 767,685

5 Claims. (Cl. 196—55)

1

This invention relates to the carbonization and gasification of solid carbonaceous material combined with the cracking of oil or other hydrocarbon material.

It is an object of this invention to process solid carbonaceous material such as coal, lignite, oil shale, and the like, and concurrently effect the cracking of hydrocarbons in a novel manner wherein substantially all the fuel requirements for both operations are taken from the solid carbonaceous material.

A further object of this invention is the provision of a novel combined process for treating solid carbonaceous materials and effecting the cracking of hydrocarbons, for example, gas oil hydrocarbons wherein the processing of fresh material, the resultant coke, and the oil are handled in a simplified and efficient manner.

Other objects of the invention will appear from the following description and claims taken in connection with the attached drawing wherein a preferred embodiment of a process according to the present invention is shown in diagrammatic form.

In its broader aspect, the present invention involves the combined carbonization and gasification of solid carbonaceous material such as coal, lignite, etc., with the production of coke, the coke being exothermically reacted, for instance, with oxygen or with hydrogen at elevated pressure to supply the heat requirements for coking fresh material and for cracking hydrocarbons derived from petroleum, coal or any other source. In the cracking of the hydrocarbon by contact with the heated coke from the gasification step, all the vaporized products thereof are conserved and the nonrecoverable solid products become combined with the coke and are thereafter processed therewith. A feature of the invention is the use of hot coke from the gasifier as contact agent for cracking hydrocarbons. The coke or solid residue drawn from the gasifier has appreciable catalytic effect on the cracking reaction.

In a specific embodiment, the invention contemplates the carbonization of carbonaceous material, gasification of coke, and cracking of oil in a fluidized system, whereby the necessary flow of heat from the gasifier to the carbonizer and the cracking unit is materially facilitated and improved.

The invention also involves the processing of the coke and oil in a manner such that the coke and the solid carbonaceous products from the oil can be efficiently utilized in the preparation

2

of desired gas mixture such as synthesis gas, consisting essentially of carbon monoxide and hydrogen, for the subsequent synthesis of hydrocarbons, oxygenated compounds and the like.

5 Referring to the attached drawing, reactors 11, 12 and 13 are of types wherein the material therein can be fluidized, the solid material being preferably charged thereto as particles of sizes less than 100 mesh and usually at least 60 per cent thereof being smaller than 200 mesh, and a fluidizing gas passed upwardly therethrough at a velocity of about 0.5 to 2.5 feet per second. Under such conditions the solids are highly agitated and the mass behaves in a manner analogous to a boiling mass of liquid. The heat exchange between the particles and the fluidizing medium is highly efficient. The boiling or ebullient action also enables the ready separation of gaseous products from the mass, any such products generated in the mass operating to further the fluidization.

Fresh solid carbonaceous material, coal being discussed herein by way of example, is fed in particle form from a hopper 14 into a line 15 into admixture with hot coke at a temperature of about 2000° F. fed to line 15 from a line 16. The conveyance of the solids is effected by suspension in a gas fed into line 15; for instance, tail gas from a Fischer-type synthesis operation 25 may be utilized. Also, this gas may be taken from the gas produced in reactor 11 by passing part of the product gas in line 31 through line 32 and pump 33 into line 15. It is desirable that the gas be relatively inert as regards the 30 solids charged to reactor 12 to the extent that little or no oxidation takes place therein.

The fresh coal and the hot coke are fluidized together in reactor 12, the temperature of the mass being above about 1000° F. and suitably 35 in the approximate range of 1400-1600° F. At this temperature, the volatile components of the coal are vaporized and removed at the top of the reactor with the fluidizing medium through a line 17. Line 17 is preferably provided with a cyclone

40 separator 20 to collect and return the solids to the reactor as shown. The gas mixture, as removed, may be used for fuel purposes or passed through a condenser 18 to separate a condensable fraction of the volatile components taken from 45 the coal. The residual gas is withdrawn through line 19. Liquid products including phenols and pyridine bases are recovered at 19a.

Coke, including both the original coke and that formed by carbonization of coal in reactor 50 12, may be withdrawn from reactor 12 and re-

turned to reactor 11 through line 21. Product coke may be taken off via line 22. Coke may also be discharged from the reactor 12 through line 24 into line 23, where it is admixed with vaporized hydrocarbon oil. Some of the coke may be returned to reactor 11 by a line 21 and some removed as product coke at 22.

The hydrocarbon oil, for example a gas oil fraction from refinery operations with an atmospheric boiling range of 525 to 760° F., is charged through line 23, hot coke being fed therein from line 16a or from line 24 or from both of them simultaneously. Preferably, the oil is preheated to a temperature of 600 to 800° F. The oil, if not supplied in vapor form, may be vaporized in line 23 by the admixture therewith of hot coke from line 16a and/or line 24. The coke is fluidized in reactor 13 by the oil vapors, the temperature of the reactor being about 900 to 1200° F. The oil is cracked by reason of the heat of and the catalytic action of the hot coke, the vaporized and cracked products being removed through line 25 through a cyclone separator 25' serving to eliminate solid particles. The coke may be returned to reactor 12 through line 26 or fed through line 27 to a gas feed line 28 for return to reactor 11. The gas or gas mixture fed through line 28 to react with and fluidize the coke in reactor 11 is dependent upon the type of product gas desired from reactor 11. If synthesis gas, consisting essentially of carbon monoxide and hydrogen, be desired, the feed gas will contain relatively pure oxygen and steam. Tail gas from a synthesizing operation containing carbon dioxide, methane and hydrogen may also be used. It is to be understood that the qualities and the quantities of the gases fed through line 28 are not critical as respects the present invention and that they may be varied widely, depending on the product gas desired.

The coke charged through line 28 is fluidized in reactor 11 and a part thereof gasified by exothermic reaction with the charged gases, the mass attaining a temperature of about 2000° F. The product gases are passed through a line 29, through a cyclone separator 30 and through line 31 to storage or use facilities such as a synthesis reactor, the hot coke being discharged through line 16 and returned to line 15 to begin the cycle anew.

From the foregoing, it is evident that the hydrocarbon oil or the products therefrom, except solid carbonaceous products, is not called upon to supply any of the heat requirements for the process. Substantially all the heat requirements are derived from the controlled exothermic reaction of the coke in reactor 11, that step being productive of a useful product in the form of the resulting gas mixture. Thus, the entire process is maintained on a high economic level.

Obviously, many modifications and variations of the invention as above set forth may be made without departing from the spirit and scope thereof and only such limitations should be imposed as are indicated in the appended claims.

I claim:

1. The process of treating a hydrocarbon oil and a solid carbonaceous material containing volatilizable constituents and a solid carbonaceous residue to produce valuable products, which comprises continuously circulating solid residue from said carbonaceous material through three intercommunicating zones, subjecting said solid residue in a gasification zone to an exothermic

gasification reaction with a gaseous reactant, passing resulting heated solid residue from said gasification zone to a carbonization zone into admixture with fresh carbonaceous material thereby effecting volatilization of volatilizable constituents from said material and formation of an additional amount of said solid residue, introducing said solid residue into a cracking zone into contact with said hydrocarbon oil thereby effecting cracking of said hydrocarbon oil with the resulting deposition of free carbon on said residue, and returning said solid residue from said cracking zone to said gasification zone wherein said carbon from said hydrocarbon oil and a portion of said solid residue is gasified.

2. A process as defined in claim 1 wherein said gaseous reactant is an oxygen-containing gas.

3. The process of treating a hydrocarbon oil and a solid carbonaceous material containing volatilizable constituents and a solid carbonaceous residue to produce valuable products, which comprise introducing said solid material in comminuted form into admixture with a fluidized mass of hot solid carbonaceous residue in a carbonization zone at a temperature sufficient to effect volatilization of volatilizable constituents therefrom and produce additional fresh solid carbonaceous residue, passing the resulting mixture of solid residue from said carbonization zone to a cracking zone and bringing into contact therewith said hydrocarbon oil while effecting fluidization of a solid residue and cracking of said oil with the resulting deposition of free carbon on said residue, passing said free carbon and said solid residue from said cracking zone to a gasification zone into contact with an oxygen-containing gas effecting fluidization and exothermic gasification of said carbon from said hydrocarbon and a portion of the solid residue thereby raising the temperature of the ungasified portion of said solid residue to a temperature above that prevailing in said carbonization zone, passing said solid residue from said gasification zone to said carbonization zone, and separately recovering gaseous products from each of said zones.

4. The process defined in claim 3 wherein said carbonaceous material is coal and wherein the temperature in the gasification zone is of the order of 2000° F., the temperature in the carbonization zone is in the range of about 1400 to 1600° F., and the temperature in the cracking zone is in the range of about 900 to 1200° F.

5. The process defined in claim 4 wherein said oxygen-containing gas is a mixture of substantially pure oxygen and steam.

EARL W. RIBLETT.
